CLAIM

The ornamental design for earphones, as shown and described.

DESCRIPTION

FIG. 1 is an isometric view of the front and left side of earphones according to the present design.

FIG. 2 is a rear elevation view of the earphones depicted in FIG. 1.

FIG. 3 is a right elevation view of the earphones depicted in FIG. 1.

FIG. 4 is an isometric view of the rear and right side of the earphones depicted in FIG. 1.

FIG. 5 is a rear elevation view of the earphones depicted in FIG. 1.

FIG. 6 is a left elevation view of the earphones depicted in FIG. 1; and,

FIG. 7 is a bottom plan view of the earphones depicted in FIG. 1.
